UNITED STATES PATENT OFFICE.

FREDERICK J. GREENE, OF RACINE, WISCONSIN.

AUTOMATIC RIVETING MACHINE.

Application filed June 25, 1920. Serial No. 391,794.

To all whom it may concern:

Be it known that I, FREDERICK J. GREENE, a citizen of the United States, and resident of Racine, in the county of Racine and State of Wisconsin, have invented new and useful Improvements in Automatic Riveting Machines, of which the following is a description, reference being had to the accompanying drawings, which are a part of this specification.

This invention relates to improvements in automatic riveting machines, more particularly adapted for riveting edge strips of angular form in cross section to panels or side members in forming trunks and similar box like receptacles.

In the present manufacture of trunks the side or panel portions are commonly nailed together along their adjacent edges or to an edge member by hand. This construction requires considerable time and is not as accurate nor as strong as machine work in which the parts are riveted together.

It is one of the objects of the present invention to overcome the before mentioned objectionable features and to provide an improved automatic riveting machine with means for holding a panel while angular edge strips are riveted thereto, and also for holding the panels while other panels are being riveted to the edge strips.

A further object of the invention is to provide an automatic riveting machine in which means are provided for automatically and intermittently moving the panel or partly assembled trunk or the like, certain predetermined distances with relation to the riveting portion of the machine to receive rivets in lines and spaced distances apart.

A further object of the invention is to provide an automatic riveting machine in which the panel or trunk part may be intermittently moved in lines backwardly or forwardly or at right angles thereto to permit the riveting of all edge portions of the trunk.

A further object of the invention is to provide an automatic riveting machine having adjustable means for automatically stopping the riveting when the last rivet of the line of rivets has been set.

A further object of the invention is to pro-

vide an automatic riveting machine which is of simple construction, is strong and durable and is well adapted for the purpose described.

With the above and other objects in view the invention relates to the improved automatic riveting machine and its parts and combinations as set forth in the claims and all equivalents thereof.

In the accompanying drawings in which the same reference characters indicate the same parts in all of the views:

Fig. 1 is a perspective view of a riveting machine embodying the improvements;

Fig. 2 is a front detail view, on a larger scale, of the mechanism for feeding the trunk parts laterally across the front portion of the machine;

Fig. 3 is a vertical sectional view taken on line 3—3 of Fig. 2;

Fig. 4 is a front detail view of one end portion of the machine;

Fig. 5 is a sectional view thereof taken on line 5—5 of Fig. 4;

Fig. 6 is a front detail view of the lower portion of the machine;

Fig. 7 is a side detail view of the parts shown in Fig. 6;

Fig. 8 is a detail sectional view of the means for transmitting motion from the driving shaft to the feeding mechanism;

Fig. 9 is a face view of the parts shown in Fig. 8;

Fig. 10 is a sectional detail view of an edge portion of a trunk showing manner of riveting the parts together;

Fig. 11 is a front detail view on a larger scale of the means for holding one of the trunk walls;

Fig. 12 is a sectional view thereof taken on line 12—12 of Fig. 11;

Fig. 13 is a sectional detail view on a still larger scale of the upper portion of the part shown in Fig. 12;

Fig. 14 is a top view of the frame part shown in Figs. 11, 12 and 13 with a trunk part mounted thereon;

Fig. 15 is a detail view of the frame for holding the side portions of the trunk while fastening to the bottom portion;

Fig. 16 is a sectional detail view taken on

line 16—16 of Fig. 15;

Fig. 17 is a sectional detail view taken on line 17—17 of Fig. 16;

Fig. 18 is a front detail view of the anvil portion of the machine;

Fig. 19 is a front detail view of the frame for holding the trunk ends while being riveted to the side portions of the trunk;

Fig. 20 is a detail sectional view thereof taken on line 20—20 of Fig. 19; and

Fig. 21 is a detail top view of the trunk part clamping means for holding parts in position while being riveted.

Referring to the drawings the numeral 15 indicates a riveting machine which comprises a base portion 26, an upstanding column 27, an outwardly and upwardly extending anvil arm 28, an outwardly and downwardly coacting hammer arm 29, a riveting hammer 30 and a rivet supply mechanism 31. The movable parts are actuated by the driving mechanism 32 mounted on and extending transversely of the upper portion of the machine. The portion of the machine thus far described, with the exception of the arm 28, is of ordinary construction and it is not necessary to show nor describe in detail.

A transversely extending guide member 33 30 rigidly mounted on the upstanding column 27 beneath the anvil arm 28 carries a slideable bar 34 which is provided with an outwardly projecting guide arm 35. The slideable bar 34 is formed with a T-shaped in 35 cross section horizontally extending slot 36 for adjustably receiving the heads of adjusting bolts 37 of the guide arm 35 to permit adjustment of said guide arm on the bar. Mounted on the upper face of the 40 guide arm 35 is a member 38 which is slideable longitudinally or at right angles to the path of travel of the guide arm 35, the member 38 being provided with threaded openings 39 to receive bolts 40 for mounting a trunk head supporting frame 41 thereon. One side edge portion of the slideable member 38 is provided with a rack 38' which is engaged by a spring actuated slideable and reversible dog 42 positioned on one side of the guide arm 35. The dog is reciprocated forwardly and rearwardly by a link and arm connection 43 with a rock shaft 44 journaled on the guide member 33. Said rock shaft is in part of rectangular 50 shape in cross section and the arm 43 is slideably connected thereto and journaled in a bearing 43' adjustably mounted on the guide member 33.

A clutch wheel 45 connected to the driving mechanism 32 carries a loosely mounted disk 46 provided with an outwardly projecting tubular wrist pin 47. The wrist pin is provided with a spring pressed bolt 48 which is adapted to enter one or the other of two bolt openings 45' formed diametrically op-

posite each other in the clutch wheel 45 to permit the changing of the time of movement of the rivet hammer with relation to the direction of travel of the slideable member 38. A connecting rod 49 having its upper end portion pivotally connected to the wrist pin 47 is provided with a manually operable lever 50 which is fulcrumed on the rod and is connected at one end to the spring pressed bolt 48 to permit the easy withdrawals of the bolt from the bolt openings in changing from one opening to the other to adjust relative movement of the parts. The lower end portion of the connecting rod is adjustably connected to a slideable member 49' which is vertically slideably mounted on the rear portion of the transverse guide 33. Said slideable member 49' is provided with a projecting pin 51 which is engaged by one arm of a bell crank lever 52 fulcrumed at right angles, with respect to the axis of the clutch wheel 45, on the transverse guide member 33. The lower arm 52' of the bell crank lever is pivotally connected to a reversible spring actuated dog 53 which is slideably mounted in the groove 54 of the transverse guide member 33. Said dog rests upon the upper edge portion of the slideable bar 34 and engages the teeth or notches 34'. The dogs 42 and 53 have their working ends of angular formation to freely snap over the teeth or recesses of their respective rack portions during their retrieving strokes, and during 60 their working strokes the dogs will positively engage the teeth and intermittently move the respective parts predetermined distances. Both dogs project through their respective supports and carry milled collars 54 having projecting pins 55 which are adapted to removably enter either one of two diametrically opposite openings 56 formed in the slideable members to reverse the directions of the working strokes. The springs of the dogs will hold the parts in 65 adjusted positions and by lifting and turning the dogs a one quarter turn the pins will rest upon the surface of the slideable members and hold the dogs out of engagement with the rack parts. The milled collars 54 are provided for convenience in disengaging the dogs from the teeth or turning them to reverse their direction of engagement.

The rock shaft 44 is journaled and supported from the opposite end portions of the transversely extending guide members 33. One end of the rock shaft 44 is provided with an upwardly extending arm 57 fast thereon which has a horizontally extending link connection 58 with a similar arm 59 mounted fast on a horizontal rock shaft 60 extending transversely across the rear portion of the machine. Said rock shaft 60 is journaled in bearings extending from the 110

- transverse guide member 33 and is provided with a downwardly and outwardly extending arm 61 which has a link connection 62 with the vertically slideable member 49'.
 5 The slideable member 49' rocks the shaft 60 through the link 62 and the arm 61, and the shaft 60 in turn rocks the square shaft 44 through the arms 57 and 59 and the link 58.
 10 A foot pedal 63 of ordinary construction controls the starting and stopping of the machine.

In order to support the load and the strain of the work the forwardly projecting guide arm 35 is provided with a downwardly depending supporting member 64 having a roller 65 journaled on its lower end which bears on the upper edge portion of the transversely extending track member 66 mounted on the base portion 26. Said supporting member 64 carries a spring retrieved foot lever 67 which has a link connection 68 with the dog 42 for conveniently disengaging said dog with its rack 38' when it is desired to quickly interrupt the forward or rearward feed of the slideable member 38.

A spring retrieved hand lever 69 pivotally mounted on the upper side portion of the column 27 extends forwardly therefrom and 30 is adapted to be releasably held in its lower position to cause the operation of the machine by engaging the lower end of a depending latch 70 which is pivoted at its upper end to the column. The foot pedal 63 is connected to said hand lever 69 by a link 63' and a link 71 connects the lever to the driving mechanism of the machine.

The slideable bar 34 has adjustably mounted thereon at its opposite ends two upstanding members 72 which are connected together at their upper ends by a transversely extending horizontal rod 73. Angular trip members 74 longitudinally adjustably mounted on the rod 73 are adapted to be moved 45 into engagement with the latch 70, when the slideable carrier has moved a predetermined distance, and swing said latch to disengage the hand lever 69 and permit said lever to swing upwardly to off position and automatically stop the operation of the machine.

In the first operation of forming a trunk section one of the panels, and preferably the bottom one A is placed on a frame 75 to receive the perforated angular edge strips 55 B preparatory to securing the side panels C to said strips. This frame 75 is clearly shown in Figures 11 to 14 inclusive and comprises an upper rectangular enclosed space 76 formed by angle irons 77 mounted on the frame. The rectangular space 76 is slightly larger than the panel to accommodate the thickness of the folded angular edge strips which are interposed between the angle irons and the edges of the panels to hold said parts in aligned position while being attached

together by the split rivets 78. The said frame 75 is adjustably mounted on leg members 79 and said members have bolts 80 which adjustably engage the T-shaped slots 36 of the bar 34. When the parts are in position the machine is actuated to feed and drive the split rivets through the perforations of the angular strips and into the panel where the split portions of the rivets are clinched as shown in Figure 10. In riveting 75 the slideable member is moved rearwardly and forwardly and the slideable bar 34 transversely until all of the strips are fastened to the edge portions of the panel. When a sufficient number of the panels have been provided with edge strips, the rectangular frame is also used to hold side panels while the angular edge strips B are being mounted on their opposite ends. When thus far completed the rectangular frame 75 is removed 85 and a rectangular frame 81 is substituted therefor which is adjustable to accommodate side panels of different widths. This frame comprises forwardly extending bars 82 which are mounted on the leg members and are connected together by a transverse bar 83. The upper ends of the leg member are also connected together by a rod 84 which has horizontally adjustably mounted thereon forwardly projecting fingers 85 provided 95 with clips 85' which engage the inner edges of the side panels C resting thereon.

The lower end portions of the leg members 79 are provided with forwardly projecting supports 86 which support the lower edges 100 of the bottom panel A and also the side panels when attached thereto. When the frame 81 is used angularly extending fingers 87 are bolted on the opposite sides of the anvil arm 28 and project upwardly and outwardly therefrom to engage the inner portion of the angular edge strips B and hold said strips in position to be riveted to the side panels C as clearly shown in Figure 17

When a predetermined number of the side panels have been secured to the bottom panels the frame 81 and the leg members 79 and the projecting supports 86 are removed and the rectangular frame 41 before mentioned and shown in Figures 19, 20 and 21, 110 is mounted on top of the slideable member 38 by the bolts 40 which extend through portions of the frame and thread into the openings 39 of said member 38. Said frame 41 is provided with forwardly projecting upper side guide members 88 and upper forwardly projecting supporting arms 89 upon which the end portions D of the trunk rest. The supporting arms 89 are provided with stops 90 against which the inner or open edges of the trunk section heads bear to properly position the partly assembled trunk section for further assembling. The side guide members 88 have their outer end portions 88' curved outwardly away from 120 125 130

each other to permit the easy entrance of the trunk section therebetween. Said curved end portions are provided with spring bell crank latches 91 which are adapted to hold the trunk section in position between the members 88 as clearly indicated in Figures 20 and 21. The springs 92 of said latches are connected thereto to swing on opposite sides of the pivotal connections of the latches and hold same in either open or closed position as indicated in Figure 21.

In using the frame 41 the end panel of the trunk section is placed on the supporting arms 89 against the stops 90 and the partly assembled trunk section is slid between the guide members 88 with the flanges of the edge strips B resting in position on the end panel. As thus positioned the said flanges may be riveted to the end panel in the same manner before described.

From the foregoing description it will be seen that with slight changes in the supporting means for the panels the trunk panels may be easily and expeditiously riveted together and that the rivets will be automatically fed, spaced apart and driven into the parts.

What I claim as my invention is:

1. An automatic riveting machine in part, comprising a slidable member having a forwardly projecting arm, a slidable member mounted on the arm, a rectangular frame removably mounted thereon, means for positioning a trunk part on said rectangular frame, means for locking the trunk parts in position on said frame, and means for intermittently moving said slidable members predetermined distances.

2. An automatic riveting machine, comprising a standard provided with riveting mechanism, a transversely extending guide member mounted on the standard, a rock shaft of rectangular shape in cross section carried by and extending longitudinally of the guide member, another shaft extending parallel thereto, a reciprocating member for rocking the last mentioned shaft, a link and arm connection between the two shafts for transmitting motion from one to the other, a slidable bar mounted on the guide member, a rack and dog and bell crank means for transmitting the reciprocal motion of

the reciprocating member to an intermittent motion of the slidable bar, said slidable bar provided with an outwardly extending guide arm, a slidable member mounted on the arm, a rack and dog and arm connection between the rectangular in-cross-section-shaft and the last mentioned slidable member for transmitting the rocking movement of the shaft to an intermittent movement of the slidable member, said arm connection slidably engaging the rectangular in-cross-section-shaft, and means on said slidable member and said slidable bar to receive interchangeable trunk part holding frames.

3. An automatic riveting machine, comprising a standard provided with riveting mechanism, a transversely extending guide member mounted on the standard, a rock shaft of rectangular shape in cross section carried by and extending longitudinally of the guide member, another shaft extending parallel thereto, a reciprocating member for rocking the last mentioned shaft, a link and arm connection between the two shafts for transmitting motion from one to the other, a slidable bar mounted on the guide member, a rack and dog and bell crank means for transmitting the reciprocal motion of the reciprocating member to an intermittent motion of the slidable bar, said slidable bar provided with an outwardly extending guide arm, a slidable member mounted on the arm, a rack and dog and arm connection between the rectangular in-cross-section-shaft and the last mentioned slidable member for transmitting the rocking movement of the shaft to an intermittent movement of the slidable member, said arm connection slidably engaging the rectangular in-cross-section-shaft, a lever normally in its off position for controlling the operation of the moving parts, means for holding the lever in its on position, means for automatically releasing the lever to permit it to swing to its off position when the slidable bar has travelled predetermined distances in either direction, and means on the slidable member and the slidable bar to receive interchangeable trunk part holding frames.

In testimony whereof, I affix my signature.

FREDERICK J. GREENE.
